UNITED STATES PATENT OFFICE.

GEORGE WILLETT, OF ENGLEWOOD, ILLINOIS, ASSIGNOR OF ONE-HALF
TO GEORGE MIDDENDORF, OF SAME PLACE.

CASH-RAILWAY.

SPECIFICATION forming part of Letters Patent No. 268,967, dated December 12, 1882.

Application filed June 26, 1882. (No model.)

To all whom it may concern:

Be it known that I, GEORGE WILLETT, of Englewood, county of Cook, and State of Illinois, have invented a new and useful Improvement in Cash-Railways for Use in Stores and other Mercantile Houses; and I do hereby declare the following to be a full, clear, and exact description of the same, reference being had to the accompanying drawings and the letters 10 and figures marked thereon, which form a part of this specification, and in which—

Figure 1 is a side elevation, showing a cash-railway containing my improvements. Fig. 2 is a section of the same on the line X X of Fig. 15. Fig. 3 is a detail section of part of the drop. Fig. 4 is a detail section of the catch attached to the outer end of the drop. Fig. 5 is a front elevation of the cash-box on an enlarged scale. Fig. 6 is a section of the box on the line y y 20 of Fig. 5. Fig. 7 is a front elevation of the elevating device. Fig. 8 is a plan view of the same. Fig. 9 is a side elevation of the same. Fig. 10 is a bottom plan view of the drop, showing device for opening and closing the same.

25 My invention relates to an improvement in devices for the transmission of money, checks, or parcels from the salesman or other employé at a point where such employé is standing to the cashier's desk, and returning the box containing such money from the cashier's desk to the point from which it started with the correct change, if any is to be returned to the customer, thereby dispensing with the expense and trouble of employing cash-boys or making 30 it necessary for the salesman to go from his station to the cashier's desk.

35 My invention consists in a cash-box attached to elastic devices, to which devices are secured carrying-wheels, suspended by said elastic 40 standards above said box, with a device for elevating the box upon the tracks, said tracks being for the purpose of carrying said box when so elevated to the cashier's desk, and returning the same to the point from which it started.

45 My invention also consists in the arrangement of guides for guiding the carrying-wheels when the box is being elevated to the track, and in the arrangement of switches on the return-track, with tripping devices on the box

and on the lower end of the return track for the 50 purpose of switching the box off the track onto the receiver or device upon which the box upon its return is to be stopped, and in various other combinations and devices used in my invention for the transmission of money or other 55 articles from the place and the room in which it is paid to the cashier's desk, all of which improvements and combinations will be particularly hereinafter described.

In the drawings, A represents the cash-box, 60 the front elevation of which is shown in Fig. 5.

B represents the carrying-wheels, by which the box is moved upon the track. These carrying-wheels are mounted on elevated spring-standards b, made of thin pieces of steel, secured to said cash-box. In the drawings three spring-standards and three carrying-wheels are shown; but I do not confine myself to that 65 number, and any desired number may be used in my invention, all of them being of equal 70 length. This box may be of any convenient size for the purposes it is intended, and the material of which it is constructed is preferably 75 of metal. On the front part of it is a lid, c, hinged to the lower side of the box. From the center of the lower side of the lid projects a 80 lip, a, as shown in Fig. 5, and a spring, e, secured by a screw to the lower side of the box, which spring extends out over the lip in such a manner as to allow the lid to open flush with the bottom of the box and to keep it in such 85 position until the cash in the box is taken out or until the amount desired is placed in the box, and when the lid of the box is closed the spring e also keeps it firmly closed. Each box 90

is numbered and has attached to its upper side a trip, v, of different length on each box, for the purpose of unlatching lever L and opening the drop at the number corresponding to the 95 number on the box.

The box A is elevated to the track by means of an elevating device, which consists of a bottom or open receptacle, E, on three of the upper sides of which are flanges projecting slightly above the upper surface. On the fourth side of this bottom the flange extends as high as the top of the box. Directly in front of this fourth flange and near it is a spring, r, made of a piece

of thin steel, and secured to the bottom of the receptacle, extending upward as high as the box. When the box is placed on this receptacle the spring is pressed back toward the flange and held in that position until the box and carrying-wheels are placed on the track and the elevator begins to descend, and when the box is released from the flanges the pressure of the spring *r* serves to give the box a slight impetus toward the cashier's desk. On either end of this receptacle are projecting ears, *e*' and *f*, as shown in Fig. 8. Passing through these ears and on each end of the receptacle are guide-rods *g* and *h*, which are secured to the track *F* in such a manner as to allow the carrying-wheels *B* to be readily guided and placed upon said track *F*. These rods are parallel to each other, and on their lower ends are nuts or heads to prevent the bottom of the carrying device from slipping off. Near the upper end of said rods is a cross-rod, *i*, fastened to both rods, and which serves to keep them in position and also forms an axle for a grooved wheel, *H*, hung in the center of said cross-rod, over which passes a cord, *p*, secured to a small ring, *j*, in front of said receptacle. To the other end of the cord is attached a heavy tassel, which serves as a handle for pulling up the box and as a balance to prevent the carrying device from descending too rapidly after the box is deposited upon the track.

From that part of the track where it is designed to place the carrying-wheels with the box are depending guides *N*, (shown in Fig. 2,) which engage with the carrying-wheels as they reach the track and serve to guide such wheels to a position on the track. These guides are placed in the same relative position to each other as the carrying-wheels. The elevating device and guides are composed of some suitable metal.

The tracks referred to are two in number, *F* and *G*. These tracks are supported by hangers *s*, as shown in Fig. 2, one end being secured to the ceiling and the other to the middle of the top of the track in such a manner as to allow the carrying-wheels to move on each side of the hangers without obstruction.

F is the conveying-track, to which is attached the above-described carrying device, and is used in conveying the money in the box to the cashier's desk, and is sufficiently inclined so as to allow the carrying-wheels with the box to move by their own gravity. When the carrying-wheels arrive at the cashier's desk the cashier takes the box from the track *F*, removes the cash from the box, and then places the box with the carrying-wheels on the track *G* for the purpose of returning them to the person who sent them. This track *G* is inclined from the cashier's desk, so as to allow the carrying-wheels to move by their own gravity, and is of the same material with the track *F* and is secured to the ceiling of the room in the same manner; but it has certain additional devices, hereinafter described, which devices are for

the purpose of allowing the cash-box to drop off from the return-track *G* at any point where it may be desired. On different parts of the returning-track *G* where it is desired to drop off the cash-box the return-track is cut on a bevel, on which is a rubber curtain to prevent noise when it closes, the cut being of sufficient length to allow the cash-box and carrying-wheels to drop onto a receiver, as hereinafter stated. That part of the track so cut which is nearest the cashier's desk is hinged to the track. Through this hinge there extends a thin flat spring, *l*, one end of which is secured to the track, the other extending far enough into the drop so that when the box drops from the track the spring will cause the drop to close immediately. The other end of the drop is secured to the track by a tripping-lever, *L*, as shown in Fig. 10 of the drawings. This tripping-lever *L* extends nearly the whole length of the drop or switch, the outer end of it extending into a catch, *t*, attached to the track, and the lever *L* is held in a position to keep the drop continually latched (except when opened by the cash-box) by means of a spring, *w*, which is fastened at one end to the bottom of the drop, the other end pressing against said lever. The other end of the lever *L* extends toward the point where the drop is hinged to the track, but is of a sufficient distance to allow the whole of the carrying device to get onto the drop before it is opened. The lever *L* is pivoted to the lower side of the track *G*.

u is a stop on the lower side of the track *G*, for the purpose of preventing the lever *L* from swinging around too far when unlatched. The inner end of lever *L* is curved in such a manner that when the trip *v* on the box strikes it, it is turned on its pivot with sufficient pressure on the spring *w*, so that it causes the lever to slip out of the catch, thus causing the drop to fall onto the receiver *K* at the point desired. The receiver *K* is level, and is used simply for the purpose of affording a convenient place to stop the cash-box. It is constructed of the same material, and is similar to the tracks *F* and *G*, except that it is level. On the farther end of this track is a bumper for the purpose of stopping the carrying-wheels, so that the salesman may remove the cash-box for further use, if desired.

The method of operating my invention is as follows: The salesman puts the money in the cash-box, after which he places the cash-box on the bottom of the elevating device. He then takes hold of the tassel attached to the cord *p* and elevates the box to the track *F*, the carrying-wheels being guided onto the track by means of the guides herein described. The box then is given a momentum by the spring *r*, and is conveyed to the cashier's desk, who takes the box, removes the money, and returning the change, if any, to the box, places the box on the track *G*, from which it is delivered by means of the devices above described, to the salesman who sent it, the

tripping devices on the track and on the box being so arranged that each box will go over all the switches but one without being switched from the track G.

5 Having fully explained the construction and operation of my improved cash-railway, what I claim as new, and desire to secure by Letters Patent, is—

1. The combination of the track F with pending guides N, secured to the track F, and so arranged as to guide the carrying-wheels B onto the conveying-track F, substantially as described and shown.

2. The combination of box A, spring-stands b, with the carrying-wheels B mounted on said standards, all constructed and arranged so as to admit of being placed on the conveying-track F, substantially as described.

3. In the elevating device, the spring r, so arranged in the receptacle E as to give the box A an impetus on the track F toward the cash-

ier's desk when the box is released from the elevating device, substantially as described.

4. The combination, in an elevating device, of the receptacle E, ears e f, guide-rods g h, 25 cross-rod i, grooved wheel H, cord p, ring j, spring r, and cash-box A, all arranged substantially as and for the purposes set forth.

5. In a cash-railway, the combination of the lever L, catch t, spring w, and stop u with the 30 drop or switch on the return-track G, for the purpose of closing and securing the drop or switch, substantially as set forth.

6. In a cash-railway, the combination of the trip v and lever L, so arranged and constructed 35 that the trip v will strike the curved end of lever L, and open the drop at the particular place desired.

GEORGE WILLETT.
